UNITED STATES PATENT OFFICE.

JACOB S. BUCKWALTER, OF PHILADELPHIA, PENNSYLVANIA, ASSIGNOR TO THE ENTERPRISE MANUFACTURING COMPANY OF PENNSYLVANIA, OF PHILADELPHIA, PENNSYLVANIA, A CORPORATION OF PENNSYLVANIA.

RELEASE CLUTCH FOR GRINDING MILLS.

Application filed July 1, 1924. Serial No. 723,534.

My invention relates to certain improvements in the clutch release mechanism for grinding mills for which application for patent was filed by Harry E. Asbury on the 5 first day of July, 1924, Serial No. 723,568.

The object of my invention is to provide a latch mechanism, which retains the rotating grinding disk and feed screw to the shaft, and which is released when the mill becomes 10 clogged, by foreign matter passing between the grinding plates.

In the accompanying drawings:

Fig. 1 is a sectional elevation of a grinding mill illustrating my invention; 15 Fig. 2 is a sectional view on the line 2—2, Fig. 1;

Fig. 3 is a detached perspective view of the shaft and the grooved collar thereon;

Fig. 4 is a detached perspective view of 20 the latch; and

Fig. 5 is a detached perspective view of the plunger that engages the latch and holds it yieldingly in position.

Referring to the drawings, 1 is the body 25 of a grinding mill having a hopper 2 and an outlet 3 for the material that has been ground. A fixed grinding disk 4 is secured to the body in any suitable manner. An electric motor 5 is secured to a flange 6 of the body 1. A motor shaft 7 is notched at the end to receive a similarly formed end of a mill shaft 8, which is mounted in a bearing 9 in a cap plate 10 that is secured to the body 1. Secured by a pin 11 to the 30 shaft is a collar 12 having a groove 13, Fig. 3. The walls of this groove are inclined, as shown clearly in the drawings, to allow the latch to be released under excessive pressure.

Mounted loosely on the shaft 8 is a feed 40 screw 14 to which is attached the rotating grinding disk 15 and the carrying disk 16. These two disks are secured to the feed screw by screws 17. Extending over the joint between the motor shaft and the mill shaft 8 45 is a sleeve 18 having a head 19. Between this head and the end of the feed screw 14 is a spring 20. There is a space 21 between the end of the sleeve and the inner end of the opening in the feed screw so that 50 the feed screw, and its disk, can be adjusted towards and from the fixed grinding disk 4. The spring 20 holds the shaft 8 yieldingly against a ball thrust bearing 22. Mounted on a stud 23 on the disk 16 is a latch 24,

Fig. 4, which has a projection 25 that is 55 adapted to fit the groove 13 in the collar 12. This projection has beveled sides 26, which fit the beveled sides of the groove 13. The bevel is such that, when the grinding disk 15 is clogged, the latch is forced out 60 of the groove. This allows the motor and the mill shaft to turn freely, independently of the grinding disk. The latch has an extension 27, which forms a finger hold by which it can be forced into the groove, or 65 manually removed from the groove. A stop 28 on the disk 16 limits the outward movement of the latch 24.

In order to hold the latch frictionally either in or out of position, a plunger 29 is 70 provided, which is adapted to slide in a projection 30 on the disk 16. Back of this plunger is a spring 31, which bears against a screw 32 in the rear of the projection. The end of the plunger is beveled, as shown in 75 Figs. 2 and 5, and either rests against one of the beveled walls 26 of the projection 25 of the latch, or in the beveled notch 33 in the latch.

When the plunger is in the notch 33, the 80 latch is held in engagement with the collar 12, as shown by full lines in Fig. 2. When the latch is raised, the plunger holds the latch out of engagement. In the present instance, the cap plate 10 has an extension 85 34, in which is mounted a cam disk 35, carrying the ball thrust bearing 22. This cam disk is prevented from turning in the cap plate. In the present instance, it has an arm 36, which enters a groove in the bearing 90 9. The back of the cam plate has three cam surfaces, which correspond to three cam surfaces on a cam block 37 that is secured to a sleeve 38, which is mounted on the extension 34 of the cap plate 10. The screws 95 39 secure the cam block to the sleeve. On turning the sleeve, the grinding disk 15 can be adjusted towards the fixed disk 4. A pin 40 which is mounted in the sleeve is projected yieldingly by a spring 41 into 100 one of a series of grooves 42 in the end of the cap plate. The means of adjusting the movable grinding disk forms no part of the present invention.

This invention is particularly adapted for 105 grinding material, such as coffee. Occasionally, the mill becomes clogged. The foreign matter enters the space between the

disks and unless there is release mechanism, one of the parts is liable to be broken. By providing the latch, as soon as the pressure is in excess of the spring pressure, the latch 5 is forced out of the groove in the collar 12 and the collar, and its shaft, turn independently of the disk. On removing the cap plate 10, the disk can be freed of the obstructions and the latch can be reset.

10 I claim:

The combination in clutch release mechanism, of a shaft; a collar on the shaft having a transverse groove therein; a movable

member mounted on the shaft; a latch pivoted to said member and having a projection extending into the groove in the collar and having a beveled wall in which is a beveled notch, and a spring-pressed plunger mounted on the movable member and having a beveled end arranged to engage the notch in 15 the latch to retain the latch in engagement with the collar, or with the beveled wall to hold the latch out of engagement with the collar.

JACOB S. BUCKWALTER.
